ASHTRAY

Benjamin K. Milbourne, 319 Winchester Road,
San Jose, Calif.

Filed June 5, 1959, Ser. No. 818,372

2 Claims. (Cl. 131—235)

This invention relates to a self-snuffing cigarette device and, more particularly, relates to any ash tray which is adapted for use in automobiles and for ash trays for other use.

As is well-known, some ash trays for automobiles have heretofore been unsatisfactory. The main source of difficulty is that many conventional ash trays provide no satisfactory means for thoroughly extinguishing a cigarette. Thus, a number of butts will collect in an ash tray and, upon putting out a subsequent cigarette, an ash will fall into the collection of butts, setting the ash tray on fire. This causes at least an unpleasant smell for the occupants of the car and may constitute an actual hazard. There is also the possibility of burning the fingers when putting out a cigarette.

It is an object of the present invention to provide for an ash tray a snuffer of simple construction wherein cigarette butts are completely extinguished before they are deposited in the tray proper.

Another object of the invention is to provide a snuffer of simple mechanical construction with relatively few moving parts.

Other objects will be apparent from the balance of the specification, which follows.

In the drawings forming a part of this application:

Figure 1 is a sectional view through an automobile dashboard, showing a preferred embodiment of the ash tray of the present invention in the retracted position.

Figure 2 is a view similar to Figure 1, showing an ash tray in the extended position.

Figure 3 is a plan view of the ash tray of the present invention.

Figure 4 is a sectional view on the line 4—4 of Figure 3.

Figure 5 is a sectional view on the line 5—5 of Figure 4.

Figure 6 is a sectional view, similar to Figure 4, but showing the position of the parts when a cigarette is discharged from the snuffer and into the ash tray.

Figure 7 is a section on the lines 7—7 of Figure 6.

Figure 8 is a detail elevation showing an alternate manner of fastening the snuffer into an ash tray.

Turning to a description of the drawing by reference characters, an ash tray on which the snuffer of the present invention can be applied has been generally designated 9 and comprises a drawer-like member 11, which is adapted to slide between the guides 13 and 15, which may be conventionally provided in automobile dashboard 17. Preferably, the front portion of the guide 13 is raised as at 19, for reasons which will be apparent. The tray is equipped with a handle, 10.

The ash tray proper is equipped with a transverse rod 21, extending between the side members 12 of the ash tray, on which is pivoted a tubular member 23. The tubular member 23 has an inside diameter somewhat larger than the diameter of a conventional cigarette and the bottom portion of the cylindrical member is cut away for most of its length, as at 25, leaving a slot there-

2

in, 27, through which a cigarette can pass freely. Slot 27 constitutes less than half of the circumference of the tubular member 23. Mounted for rotation in the cylindrical member 23 is a rod-like member, 29, which is somewhat longer than the member 23 so that it extends beyond the member 23, as at 31. One end of the rod-like member 29 has an annular groove 33 formed therein. The tube 23 has a hole 24 transversely therethrough but off-center and the rod 21 passes through the hole 24 in the tube 23 and also lies in the annular groove 33. This holds the parts in assembled relationship yet allows the free turning of the rod 29 with respect to the tube 23. The rod 29 also has a groove 35 throughout most of its length, but which terminates short of the annular groove 33, said groove 35 being of sufficient size to receive a cigarette when in assembled relationship with the tube 23.

A flat spring 37 extends from the back of the tube 23 to the rear portion of the ash tray 11 so that the tube assembly is normally urged upwardly. Thus, when the ash tray is pulled out, the spring 37 causes the tube assembly to tilt upwardly to a convenient angle, as is shown in Figure 2, while when the ash tray is retracted, the cam action of the part 19 causes the tube assembly to move downwardly into the ash tray, as is shown in Figure 1.

Instead of pivoting the snuffer in an ash tray, other fastening means can be employed. For instance, in Figure 8, the tube 23 is provided with a recess 24 into which a coil spring 26 is fastened; the spring can be clipped over the side or back of an ash tray. The coil spring may be fastened into recess 24 by a weld or merely by having a friction fit.

To use the device, the ash tray is pulled out and the rod 29 is rotated to the position shown in Figures 4 and 5, and the lit end of a cigarette, 39, is inserted through the open end of rod 29 into the groove 35. As will be apparent from Figure 4, the burning portion of the cigarette is thus placed in a confined space with substantially no access to air. If the cigarette is left in this position for a few seconds, it will be thoroughly extinguished and it is then only necessary to rotate the rod 29 with the fingers to the position shown in Figures 6 and 7, and the extinguished cigarette 41 will be discharged into the bottom of the ash tray.

Although this invention has been described in conjunction with an ash tray for use in a vehicle, it is quite obvious that the principle here described can be used in many other environments.

I claim:

1. A cigarette snuffer consisting of a unitary structure including a tubular member open at one end and having a slot therein, said slot being of sufficient size to allow a cigarette to pass freely therethrough but constituting less than half the circumference of the tubular member; a smaller rod-like member mounted for rotation in the said tubular member, said rod-like member being somewhat longer than said tubular member and extending beyond the open end of said tubular member, said unitary structure being mounted for pivotal action on a transverse rod, said rod being mounted on the sides of an ash tray, there being an annular groove in said rod-like member, said groove providing a receptacle for said transverse rod when said unitary structure is rotated; a second groove in said rod-like member, said second groove terminating short of said annular groove and being of sufficient size to receive a cigarette at its open end when in assembled relationship with the said tubular member, said unitary, rotatable structure being so mounted whereby in a first position a cigarette may be confined in the second groove of the rod-like member, may be rotated to a second position whereby said second

groove is lined up with said slot in said tubular member and the cigarette discharged through said slot.

2. The unitary structure of claim 1 wherein said structure is mounted in a vehicle ash tray of the sliding drawer type, said vehicle having a panel having guides for said sliding drawer ash tray, one of said guides having an upturned front end, said structure bearing against a spring extending from the tubular member to a wall of said ash tray and being secured thereto, said spring urging the unitary structure upwardly when said ash tray

5
10

is drawn out on said guides and downwardly by the cam action of the said upturned front end into the ash tray when said ash tray is retracted into the dashboard of a vehicle.
